UNITED STATES PATENT OFFICE.

CONRAD KNOTH, OF NEWARK, NEW JERSEY, ASSIGNOR TO HYATT ROLLER BEARING COMPANY, A CORPORATION OF NEW JERSEY.

ELECTRIC RIVETING-MACHINE.

1,128,690.

Specification of Letters Patent. Patented Feb. 16, 1915.

Application filed September 26, 1914. Serial No. 863,710.

To all whom it may concern:

Be it known that I, CONRAD KNOTH, a citizen of the United States, residing at 173 Jelliff avenue, Newark, county of Essex, 5 and State of New Jersey, have invented certain new and useful Improvements in Electric Riveting-Machines, fully described and represented in the following specification and the accompanying drawings, forming a 10 part of the same.

This invention relates to an improved means for electrically heating the heads of rivets while pressing the heads upon the parts which they connect.

15 The improvements relate to a flat table upon which the work-piece may be moved without loosening its electrical connection, means for adjusting the ram-moving lever into a convenient position for the operator, 20 whatever the height of the work-piece upon the table, means for movably connecting the electric conductor with the movable electrode, special means for cooling the bed and the movable electrode, and other details of 25 construction which will be understood by the following description.

The circuit wires are connected to the movable die-holder by movable conical joints which maintain a perfect connection 30 for the current, while permitting the movement of the joint as the die-holder moves the "set" vertically when riveting. The die or "set" upon the die-holder forms an upper electrode, and the work-table forms a 35 lower electrode by which the current is conducted to the parts to be welded, and such die-holder and work-table may, if desired, be made with internal passage or chamber connected with a water-supply, so as to conduct away the heat which is absorbed by such parts. The bed is supported upon a 40 metallic frame and a transformer supported upon such bed or frame and supplied with generator connections. A conductor for the current is extended from the transformer directly to the die-holder, but a switch is interposed in the generator connection of the 45 transformer, which switch is held normally open and actuated by a treadle so that the circuit may be closed through the work-table, the rivet and the die-holder at the 50 pleasure of the operator.

The invention will be understood by reference to the annexed drawing, in which—
55 Figure 1 is a side elevation of a riveter

embodying the invention, with the leg F' at the nearer side of the work-table removed, and the edge of the frame broken away before the switch q. Fig. 2 is a side elevation of the same with the leg at the 60 nearer side of the work-table removed and the frame in section at line 2—2 in Fig. 1; Fig. 3 is a plan of the bed and work-table; Fig. 4 is a central transverse section of the work-table with the detachable seat fitted 65 thereto; Fig. 5 is a side elevation of the ram; Fig. 6 shows the bottom end of the ram; Fig. 7 is a front view of the die-holder head; Fig. 8 is a plan of the same, and Fig. 9 is a vertical section of the die, 70 the die-holder and the head which connects the same to the ram. Fig. 10 is a horizontal section, where hatched, on line 10—10 in Fig. 2, and Fig. 11 is a vertical section, where hatched, on line 11—11 in 75 Fig. 10.

A designates the bed-plate of the machine supported upon a suitable stand, and B the work-table secured upon the same and sustained upon a seat B' by an insulating 80 packing B². The bolts B³ which secure the table to the bed are extended through insulating sleeves b³, shown only in Fig. 3.

The guide for the ram or plunger C is formed with a body D, an adjustable cap D' 85 and an ear E upon its rear side, to which a leg F is jointed. It is also provided with bosses G at opposite sides to which tubes or legs F are fitted and extended to sockets G' upon the bed-plate. Bolt-rods having heads 90 beneath the bed are extended through the pipes F' and secured in the bosses G. The leg F is formed of a pipe connected by right and left hand threads at its opposite ends to joint-pieces F², one of which is 95 hinged to lugs E' upon the bed-plate. The legs F and F' slope outwardly from the guide body D, to leave ample space above the table B, and the desired setting of the guide is facilitated in the manufacture 100 of the machine by making the leg F adjustable as to length.

The bed A is formed with flanges A' beneath its margin having notches A² to rest upon pipes H forming the top of a rectangular stand, and caps a clamp the bed to the pipes by means of bolts a'. The stand has pipe-legs I connected by ties J and K.

The ram C is provided upon the lower end with a shank C' to which a head c is 110

secured to carry the die-holder *d* and die or "set" *e* which is used to press the rivet in the riveting operation. The die and die-holder form the upper electrode. The head 5 *c* is secured upon the shank *C'* by a bolt *f* having notch at the middle of its length to clear the shank but is drawn against the same when desired by a nut *f'*. The head is formed with a horizontal water-chamber *g* having an inlet connection *g'* at one side and an outlet connection *g''* at the opposite side. A threaded socket *h* is formed in the bottom of the head to receive a threaded shank upon the die-holder *d*, which is 10 formed with a conical nozzle to which a tapering socket upon the die or "set" or movable electrode is fitted removably, but formed with such angle that the friction keeps the parts in engagement when in use. 15 The "set" or die is formed with an extension *e'* at the bottom which may be ground off from time to time as it becomes roughened by use. Special means is provided to circulate water through the chamber *g* to 20 cool the parts which become heated by the electric current, and the center of the holder *d* is formed with a bore *d'* communicating with the water-chamber *g* so as to cool the die-holder and the "set." The die or "set" 25 becomes much more highly heated than the table, as the area of contact is so much smaller in the "set" than where the work-piece rests upon the table; but if required, the table *B* may also be formed for the circulation of water, as shown in Fig. 4. The 30 table is made with an annular water-chamber *u*, and water-pipes *v* and *v'* are connected with the opposite sides of such chamber. In practice, the same water is circulated 35 through the table and through the head *c*, the water being introduced, as indicated by the arrow *w* in Fig. 4, at one side of the table and thence carried from the pipe *v'* to the pipe *g'* upon one side of the head, 40 being discharged therefrom through the pipe *g''*.

The ram *C* is of diamond-shape, and the body *D* of the guide, as shown in Fig. 10 is formed to fit the rear side of the ram, 45 while the cap *D'* fits the front side. The rear corner of the ram is flattened as shown in Fig. 6, and teeth *h* cut therein, as shown in Fig. 5, to fit a pinion *i* upon a spindle *j* which is extended through a bearing *D'* upon 50 the guide and provided at one end with a hand-lever *M* for rotating the pinion. The spindle is reduced to form a clearance-space *k* at one end of the pinion, and the end of the spindle adjacent to such pinion is provided 55 with grooves *l* and *l'*, to which a spring-plug *m* is fitted. When the plug is fitted to the inner groove *l* it holds the pinion in engagement with the teeth *h* upon the ram, as 60 shown in Fig. 10, but the pinion may be 65 cleared from the teeth of the ram by lifting

the spring-plug with a hand-knob *n* and moving the spindle lengthwise, as shown in Fig. 11, until the plug engages the groove *l'*. This sets the clearance-space *k* in line with the rear edge of the ram and clears the rack 70 of teeth from the pinion. This construction is designed to facilitate the adjustment of the ram at different heights above the table to operate upon work-pieces of different heights, when the hand-lever *M* is at the 75 right hand side of the operator, in the position shown in Fig. 1.

In Fig. 1, a work-piece is shown upon the table consisting of a jig-block *N* in which a series of tie-rods are supported in proper 80 relation to apply a ring *o* to the upper ends of the rods *o'* and rivet the ends of such rods upon the outer side of the ring. It is obviously an advantage to move the "set" as short a distance as possible during the riveting operation, and the construction of the spindle and pinion permits the ram to be moved freely up and down until the "set" and the hand-lever are in the proper adjustment, when the pinion can be reengaged 90 with the ram.

The machine is adapted for use with electric light circuits having a voltage of 220 volts or over, by locating a transformer *V* upon the bed or frame of the machine, which 95 greatly reduces the voltage and increases the current to pass through the rivet. Such a transformer is shown secured to the rear legs *I* of the stand, and receiving its current from the generator by line-wires *W*. A plurality of conductors *W'* is extended from the transformer to the opposite sides of a lug *r* formed upon the rear of the head *c*, and each attached to a conical hub *r'* fitted movably in conical sockets in opposite sides of 100 the lug. These hubs are pressed into the socket by an adjusting through-bolt *r''* which furnishes a means of adjusting the pressure of the conical hubs in their sockets and thus securing a close electrical connection without unnecessary friction. To carry 105 the current to the work-piece, a renewable seat *s* is fitted to a counter-bore in the table *B*, and provided with a shank *s'* extended downward through a clearance-hole *s''* in the bed *A*, and a current connection *V'* is extended from the transformer to such shank. 110 As the table *B* and the shank *s'* are insulated from the bed they form conjointly the lower electrode, and the current is thus confined to the head *c* and to the table *B*, and the conduction of the electric current to other parts of the machine is thus avoided.

A switch *q* is provided in the generator 115 connections to the transformer as usual, and operated by means of a treadle *T* and rod *t* to close the generator-circuit during the riveting operation. The riveting is performed by pressing the "set" by the lever *M* against the metal to be riveted, then closing the cir- 120 125 130

cuit by the treadle T which heats the rivet as desired, and then forcing the "set" downward by the lever M and simultaneously opening the circuit by the treadle T.

5 The transformer is omitted from Fig. 2 and indicated in dotted lines in Fig. 3, and the generator connections W carry the current to the same through the switch-lever q which is operated by the rod t extended 70 upward from the treadle. The switch is attached to an insulating plate r upon the under side of the bed, the flange of which is broken away in Fig. 1 to exhibit the switch. Such location of the switch protects it from 75 derangement and shortens the connections to the transformer and the table B.

A flat plate or leaf U to support the work-pieces for riveting is shown in Fig. 2 supported upon pipes H' extended sidewise 20 from the fittings L at the ends of the pipes H, and such pipes H' may be connected with an adjacent pipe-stand of similar character for another riveting machine, a series of such machines being thus connected together 25 and their stands or frames serving to support plates or leaves between the respective machines to carry the articles for riveting.

It will be observed in Fig. 4 that the inlet-pipe v introduces water to the chamber u 30 in the work-table at a lower level than the outlet v' discharges it, and the same is true, as will be observed in Fig. 7, of the inlet g' and the outlet g² connecting with the horizontal chamber g in the head c, which carries the "set." These differences of level, 35 it is found in practice, greatly facilitate the circulation of water through the table and the head to cool the same, which is very desirable where a supply of water is taken 40 from a tank, and used over and over without renewing. Where the supply is taken from an aqueduct and runs to waste after operating in the machine, such construction would not be so material; but the waste of 45 water is avoided by providing a small tank in any convenient location.

The conical joints which connect the conductors w' with the head c not only form a more perfect contact than flat joints, but 50 permit the joints to rock or oscillate a little upon the head when the ram C is moved up and down, as occurs constantly in practice. The bolt r² can be tightened sufficiently to produce a perfect contact and leave the cones 55 r' free to also turn in their sockets. Such details of construction are of great value in preventing the short-circuiting of the current, the burning out of the transformer, the reduction of the current transmitted to 60 the "set," the convenience of operating, and the reliability of the machine.

Having thus set forth the nature of the invention what is claimed herein is:

1. In an electric riveter, the combination, 65 with a lower electrode, of a ram movable to

and from the same and having a head carrying the upper electrode, and current conductors extended to opposite sides of the head with movable conical hub-and-socket joints connecting the terminals of said conductors 70 with the opposite sides of said head, and means extending through the hubs and sockets for adjusting the pressure of the hubs in the sockets to form a perfect movable electrical contact when the head is raised and 75 lowered by the ram.

2. In an electric riveter, the combination, with a support for the work-piece, of a diamond-shaped ram carrying a riveting die and having a rack formed upon one of its corners, a fixed guide for such ram with cylindrical bearing transverse to the rack and a spindle rotatable in such bearing, and a pinion to mesh with the rack having a clearance-space at one end of the pinion, and 80 means for holding the pinion in mesh with the rack, when desired.

3. In an electric riveter, the combination, with a bed, of a table secured thereon with suitable insulation and fastenings, a counterbore in the table, and a removable flat seat filling such counterbore and provided with an electrical connection to form a flat support for a work-piece, a guide secured above the bed with ram therein movable to and 95 from the table, and a head upon the ram with an upper electrode secured thereto.

4. In an electric riveter, the combination, with a bed, of a table secured thereon with suitable insulation and fastenings, and having a passage extended therethrough and through the bed, and an enlarged counterbore in the table at the top of such passage, a removable seat filling such counterbore and having a shank extended through the 100 said passage to receive an electrical connection, a guide secured above the bed with ram therein movable to and from the table, and a die-holder and die carried by the 105 head.

5. In an electric riveter, the combination, with a bed having a work-table insulated thereon, of a guide with ram movable therein to and from the bed, a die-holder carried by the ram and supplied with an electrical connection, sloping tubes fitted between the guide and the bed at the sides of the ram and bolt-rods connecting the guide with the bed through such tubes, and an adjustable leg connecting the rear of the 115 guide with the rear of the bed, substantially as herein set forth.

6. In an electric riveter, the combination, with a bed, of a table insulated thereon and formed with a water-channel, a ram movable to and from the table and having a head with water-passage therein and a die-holder secured upon the head, a pipe connecting the water-channel in the table with the water-passage in the head, and means for 125 130

circulating the water successively through said parts.

7. In an electric riveter, the combination, with a bed, of a table insulated thereon and formed with a water-channel having inlet and outlet-connections at different levels, a die-holder secured upon the head and having a head with water-passage therein and a die-holder secured upon the head and having a water-channel connected with the water-passage, water-connections from such water-passage at different levels, a flexible pipe joining the upper connection of the table to the lower connection of the head, and means for circulating water successively 15 through the said parts.

In testimony whereof I have hereunto set my hand in the presence of two subscribing witnesses.

CONRAD KNOTH.
